(57) **CLAIM**

The ornamental design for a bowling alley table, as shown
and described.

DESCRIPTION

FIG. 1 is a top plan view of a bowling alley table showing
my new design;

FIG. 2 is a side elevational view thereof of the bowling alley
table of my design; and,

FIG. 3 is a top perspective view of a bowling alley table of
my design.

The broken lines in the drawings form no part of the claimed
design.
